UNITED STATES PATENT OFFICE.

EUDOLPH COOPERSMITH, OF ST. LOUIS, MISSOURI, ASSIGNOR, BY MESNE ASSIGNMENTS, TO COOPERSMITH BED COMPANY, OF ST. LOUIS, MISSOURI, A CORPORATION OF MISSOURI.

SOFA BED.

Application filed August 3, 1925. Serial No. 47,652.

This invention relates to sofa-beds and has for its principal object to produce a strong and durable light weight sofa-bed which is readily converted for use as a bed or couch or divan and will not accidentally close when opened as a bed. Other principal objects are to provide for simplicity and cheapness of construction of such device, to permit the use of coiled spring bed bottoms; and to provide ample and easily accessible storage space for bed accessories.

The invention consists in the parts and combinations and arrangements of parts hereinafter described and claimed.

15 In the accompanying drawings, which form part of this specification, and wherein like symbols refer to like parts wherever they occur,

20 Fig. 1 is a plan view of one end portion of a sofa-bed embodying my invention, the device being shown converted into a bed,

Fig. 2 is an end view showing the device fully opened, as a bed,

25 Fig. 3 is an end view showing the device partly opened, and

Fig. 4 is an end view showing the device folded as a sofa or divan.

The sofa-bed shown in the accompanying drawings comprises a rigid sofa frame A 30 and folding bed frames or sections B and C, said frames being preferably composed of angle irons. The sofa frame A comprises four legs or corner posts 5 mounted on casters 6 and suitably connected by side rails 7 and end rails 8. The sofa frame is provided 35 at its corners with diagonal braces 9 which constitute supports for the folding section or frame C in the closed position thereof.

40 In the unfolded or opened position of the sofa-bed, as shown in Fig. 2, the bed frames B and C are disposed in substantially the same horizontal plane and cooperate to form the bed bottom. In the folded or closed position of the sofa-bed, as shown in Fig. 4, 45 the outer bed frame B forms the seat portion of the sofa-bed and the inner bed frame C is folded beneath said outer section B and forms a support for bed accessories, such as mattresses, pillows and bed clothing.

50 Each of the folding frames B and C are provided with a spring bottom consisting of vertically disposed coil springs 10, prefer-

ably of conical form, that are supported in spaced relation by a wire fabric 11 connected to the side and end rails of each frame. 55 A mattress 12 covers the frames B and C in the unfolded or bed positions thereof. In the folded or closed position of the sofa-bed, the outer portion of the mattress 12 is folded upon the inner portion thereof and the 60 entire mattress is supported on the inner frame C and is thus concealed below the outer frame B, which forms the seat portion of the sofa-bed.

The outer frame B is provided at its outer 65 corners with legs 13 adapted to support the outer portion of said frame in the bed position thereof. The legs 13 of the outer section are suitably connected to the side and end rails thereof by diagonal stays which 70 serve to brace and stiffen the outer corners of said frame. The outer bed frame B is pivotally connected at each end to the sofa frame by means of a pair of horizontally 75 pivoted parallel links 14, the pivots of the links of each pair being equidistant so that 80 said frame remains in a horizontal position in any position of its swinging movement. The upper ends of parallel links are pivotally connected to angle irons 15 secured to 85 the underside of the end rails of the outer bed frame B adjacent to its inner corners, and the lower ends of said links are pivotally connected to the lowermost end rails of 90 the sofa frame adjacent to the outer corner thereof. As shown in the drawing, the outer ends of the outer links are secured to the depending ends of bracket members 16 that extend into the ends of tubular bars 16^a and are riveted or otherwise rigidly 95 secured thereto, the ends of said bars being journaled in holes provided therefor in the brackets 16. The bracket members 16 of the outer frame B are provided with stop pins 17 adapted, in the unfolded or bed position 100 of said frame to abut against the upper surfaces of the outermost supporting links and thus prevent the inner end of said frame from swinging downwardly. The lower portions of the inner links are extended beyond 105 their supporting pivots and are provided with short links 18. Coil springs 19 are secured to the links 18 and to the diagonal braces 9 at the rear corners of the sofa

frame A and serve to assist in the unfolding movement of the outer frame and to check or cushion the closing movement thereof and thereby prevent jarring of the parts.

The inner bed frame C is also connected at each end to the adjacent ends of the sofa frame by a pair of parallel links 20. These parallel supporting links have pivotal connections at their upper ends with the rear end portions of the end rails of the inner bed frame C; and the lower ends of said links are pivotally secured to the lowermost end rails of the sofa frame A at points adjacent to the lowermost pivots for the parallel links 14 that connect the outer frame B to said sofa frame. The pivots of each pair of parallel links 20 are equidistant and the inner frame C will therefore be in a horizontal position in all positions of its swinging movement. The rearmost links of the pairs of supporting links 20 have angular extensions 21^a provided at their free ends with horizontal extending pins 22 adapted to be engaged by the inner links of the pairs 14 during the unfolding of opening movement of the outer bed frame B and thus cause the links 20 to swing upwardly and raise the inner bed frame C to bed position. The pins 22 on the angular extensions 21^a of the rear links of the pairs 20 bear against the front edges of the rearmost links of the pairs 14 during the folding or closing movement of the bed frames and thus permit the inner bed frame C to return to its folded position gradually and without jar. Braces 23 extend across the angle formed by the extensions 21^a of the links 20 and thus serve to brace and stiffen the same. Said braces also serve to keep the links 21^a in line with the pins 22 on the links 14.

Pivots secured to the rearmost links of the pairs of links 20 are latch arms 21, whose free end portions are slidably supported in notches 24 provided therefor in the front corner posts of the sofa frame A and are provided at their lower edges with notches 25 adapted, in the bed position of the inner frame C, to straddle the bottoms of the notches 24 in said corner posts and thus prevent swinging movement of the frame C. The latch arms 21 extend forwardly beyond the sofa frame A and are adapted to be released, at the beginning of the closing movement of the outer frame B, by means of pins 26 secured to the front links of the pairs of links 14 that pivotally support the outer frame B.

The device may be easily opened to bed position, as shown in Fig. 2, by grasping the outer bed frame B and drawing the same forwardly out of the stationary sofa frame A. The outer frame B, by reason of its parallel link connections 14 with the sofa frame A, is carried forward in a horizontal

position until the inner links of the pairs 14 abut against the pins 22 on the angular extensions 21^a of the rearmost links of the pairs 20 and cause the same to swing upwardly and raise the inner bed frame C to bed position. In this position of the inner bed frame C, the notches in the latch arms 23 straddle the upper edge of the sofa frame and thus prevent accidental closing movement of the bed frame. The inner section is unlocked by raising the outer frame B on its supporting links 14, which action causes the pins 26 to engage the forward ends of the latch arms and thus cause said arms to become disengaged from the sofa frame; whereupon the inner section gradually returns to its folded position by reason of the engagement between the pins 22 and the supporting links 14 for the outer section B.

It is noted that the hereinbefore described arrangement provides ample space between the folded frames B and C for the stowage of the folded mattress 12 and other bed accessories and for accommodating the coil spring bottoms 19, which require more space than is ordinarily provided between the folded bed sections of sofa-beds. It is also noted that the folding bed frames separate quickly at the beginning of their opening and closing movements, and thereby prevent snagging of the bed accessories by said frames.

Obviously, the hereinbefore described device admits of considerable modification without departing from the invention; therefore, I do not wish to be limited to the precise arrangements shown and described.

What I claim is:

1. A sofa-bed comprising a sofa frame, a seat section and an inner section below said seat section, horizontally pivoted parallel link connections between each of said sections and said sofa frame, whereby said sections are adapted to be swung into the same horizontal plane to form the bed bottom and remain in a substantially horizontal position in all positions of their swinging movement, and a latch arm secured to one of the supporting links for said inner section and adapted to cooperate with said sofa frame to hold said inner section in bed position.

2. A sofa-bed comprising a sofa frame, a seat section and an inner section below said seat section, horizontally pivoted parallel link connections between each of said sections and said sofa frame, whereby said sections are adapted to be swung into the same horizontal plane to form the bed bottom and remain in a substantially horizontal position in all positions of their swinging movement, and a latch arm secured to one of the supporting links for said inner section and adapted to cooperate with said sofa frame to hold said inner section in bed position, said latch arm being adapted to be dis-

- engaged from said sofa frame by one of the supporting links for said seat section during the return thereof to seat position.
3. A sofa-bed comprising a sofa frame, a seat section and an inner section below said seat section, separate pairs of horizontally pivoted parallel link connections between each of said sections and said sofa frame, whereby said sections are adapted to be 10 swung into the same horizontal plane to form the bed bottom, and a locking device movable with said inner section and adapted to cooperate with said sofa frame to hold said inner section in bed position, said locking device being adapted to be disengaged from 15 said sofa frame by one of the supporting links for said seat section during the movement thereof to seat position.
4. A sofa-bed comprising a sofa frame, a seat section and an inner section below said seat section, separate pairs of horizontally pivoted parallel link connections between each of said sections and said sofa frame, whereby said sections are adapted to be 20 swung into the same horizontal plane to form the bed bottom, a locking device movable with said inner section and adapted to cooperate with said sofa frame to hold said inner section in bed position, and means operated by the movement of said seat section to seat position for disengaging said locking device from said sofa frame.
5. A sofa-bed comprising a sofa frame, a seat section and an inner section below said seat section, and horizontally pivoted parallel link connections between each of said sections and said sofa frame, whereby said sections are adapted to be 25 swung into the same horizontal plane to form the bed bottom, one of the links for the inner section having an extension adapted during the opening movement of said seat section to be engaged by one of the supporting links for said seat section to cause said inner section to move to bed position, one of the links for the inner section having an extension adapted during the opening movement of said seat section to be engaged by one of the supporting links for said seat section to cause said inner section to move to bed position, 30 and said sofa frame, whereby said sections are adapted to be swung into the same horizontal plane to form the bed bottom, the link connections between said inner section and
- said sofa frame having portions adapted during the opening movement of said seat section to be engaged by the link connections between said seat section and said sofa frame to move said inner section to bed position, and means carried by one of the links for the inner section for locking said section in bed position.
6. A sofa-bed comprising a sofa frame, a seat section and an inner section below said seat section, horizontally pivoted parallel link connections between each of said sections and said sofa frame, whereby said sections are adapted to be 35 swung into the same horizontal plane to form the bed bottom, the link connections between the inner section and the sofa frame having portions adapted during the opening movement of said seat section to be engaged by the link connections between the seat section and said sofa frame to move said inner section to bed position, means carried by one of the links for the inner section for locking said section in bed position, and means whereby one of the links for the seat section is adapted to release said locking means during the return of said seat section to its closed position.
7. A sofa-bed comprising a sofa frame, a seat section and an inner section below said seat section, horizontally pivoted parallel link connections between each of said sections and said sofa frame, whereby said sections are adapted to be 40 swung into the same horizontal plane to form the bed bottom, one of the supporting links for the inner section having an extension adapted during the opening movement of said seat section to be engaged by one of the supporting links for said seat section to cause said inner section to move to bed position, the extension of the supporting link for said inner section being shaped and arranged so that the inner section is caused to start its movement to bed position after the seat section has completed the greater portion of its movement to bed position and said inner section is caused to return to its folded position before said seat section reaches its folded position.
8. A sofa-bed comprising a sofa frame, a seat section and an inner section below said seat section, horizontally pivoted parallel link connections between each of said sections and said sofa frame, whereby said sections are adapted to be 45 swung into the same horizontal plane to form the bed bottom, the link connections between said inner section and

Signed at St. Louis, Missouri, this 1st day of August, 1925.
